US00D771111S

(12) **United States Design Patent** (10) **Patent No.:** **US D771,111 S**
Roberts et al. (45) **Date of Patent:** **** Nov. 8, 2016**

(54) **DISPLAY SCREEN WITH GRAPHICAL USER INTERFACE**(71) Applicant: **Microsoft Corporation**, Redmond, WA (US)(72) Inventors: **Chad Michael Roberts**, Snohomish, WA (US); **Andrea Michelle Simons**, Shoreline, WA (US); **Janis J. Lee**, Kirkland, WA (US)(73) Assignee: **Microsoft Corporation**, Redmond, WA (US)(***) Term: **14 Years**(21) Appl. No.: **29/465,677**(22) Filed: **Aug. 30, 2013**(51) LOC (10) Cl. **14-04**

(52) U.S. Cl.

U.S. Appl. No. 29/462,865, filed Aug. 9, 2013, Display Screen with Graphical User Interface.

(Continued)

Primary Examiner — Ian Simmons*Assistant Examiner* — Shannon Morgan(74) *Attorney, Agent, or Firm* — Banner & Witcoff, Ltd.(57) **CLAIM**

The ornamental design for a display screen with graphical user interface, as shown and described.

DESCRIPTION

FIG. 1 is a front view of a first embodiment of a display screen with graphical user interface showing our new design; and,
FIG. 2 is a front view of a second embodiment of a display screen with graphical user interface showing our new design.

1 Claim, 2 Drawing Sheets# US D771,111 S
